UNITED STATES PATENT OFFICE.

CHARLES F. HAUG, OF ST. PAUL, MINNESOTA.

SANDPAPERING-MACHINE.

1,060,595.

Specification of Letters Patent.

Patented May 6, 1913.

Application filed July 5, 1912. Serial No. 707,935.

To all whom it may concern:

Be it known that I, CHARLES F. HAUG, a subject of the King of Norway, residing at St. Paul, in the county of Ramsey and State 5 of Minnesota, have invented a new and useful Sandpapering Machine, of which the following is a specification.

My invention relates to sandpapering machines, and the object is to provide an efficient device which carries its own power 10 appliance and may be moved by hand upon window casings and sills of railway coaches and other structures for sandpapering the surface thereof.

15 In the accompanying drawings.—Figure 1 is a top or plan view of my sandpapering machine with a portion of its electric motor broken away. Fig. 2 is a side elevation of the machine with a portion of one of its 20 handles broken away. In said view the machine is shown as resting upon a piece of lumber to be sandpapered. Fig. 3 is a transverse section on the line, *a—a* Fig. 1 with the handles and runners of the machine 25 omitted. Fig. 4 is a bottom view of one of the slides 37 and the eccentric and shaft therein.

Referring to the drawing by reference numerals, I provide a skeleton frame 30 composed of longitudinal side pieces 1, 1^a, secured together by transverse bars 2, 3, 4. Said frame is provided with side handles 44 and four lugs 5, in which slide vertically four posts 6, whose lower ends are secured 35 in two runners 7; each post has a head 8 above the lug and a partly compressed coil spring 6^a encircling it below the lug, whereby the runners are yieldingly held downward.

40 In slots 9 in the frame are slidably supported the tenons or ribs 10 of a block 11, which is reciprocated by a pitman 12 having one end pivoted at 13 to the block and its other end connected with a crank shaft 45 14, which is journaled across the frame, and has at one end fixed a gear wheel 15, which is driven by an idler gear 16; the latter is driven by a pinion 17, fixed at one end of the shaft 18 of an electric motor 20, 50 which is secured at 21 upon the frame and connected with electric circuit wires 22 (see Fig. 2) of a suspended cable 23, which permit moving of the device to any desired part of the work operated on.

The idler gear 16, which is mounted on a 55 stud 24 fixed in a stand 25 in the frame, also drives a gear 26 on the shaft 27 of a roller 28. Said roller has a longitudinal side groove 29, in which a slightly tapered key 30 is inserted and serves to hold the 60 inserted edges 31 of a sheet of sandpaper 32, which is stretched about the roller. The lower and slightly lengthened portion of the block 11 is also covered with sandpaper 33, which paper, as best shown in Fig. 3, has its 65 lateral edges 34 firmly held in recesses 35 of the block by broad hooks 36 of two sliding plates 37, which are fitted to slide one upon the other in a transverse slot 38 in the block. Said overlapping plates are each provided 70 with a slotted hole 39 (see Fig. 4), in which is fitted an eccentric 40. Said eccentrics are fitted on a small vertical shaft 41, which is journaled in the block and has its upper end provided with a springy horizontal arm 42, 75 engaging a segmental toothed rack 43 upon the block. It is obvious that by swinging the arm 42 into different notches the eccentrics will draw the hooks 36 tightly against sandpaper of different thickness. 80

It is evident that where compressed air power is obtainable a compressed air motor may take the place of the electric motor shown.

In the operation of the machine the motor 85 is first started, and then the operator grasps the handles 44, one in each hand, and pressing the runners 7 against the wood that is to be sandpapered, as against the strip 45 in Fig. 1, until the sandpaper covering the 90 roller 28 and block 11 touch the surface of the wood, he then moves the machine along upon the surface while the roller with its coarse sandpaper does the rough part of the work and the reciprocating block comes 95 after and finishes the work by finer sandpaper. In this manner sandpapering may be done very fast and on level, upright, slanting or overhead surfaces. 100

What I claim is:

A sand papering machine comprising a movable frame having handles adapted to be held by the hands of the operator, a rotating roller, mounted in the frame and having means for holding sandpaper detachably secured about it, and a motor mounted on the frame and operatively connected with the roller, a crank shaft journaled in

the frame and rotatably connected with the
motor, a block slidably mounted in the
frame, and having means for detachably
holding sandpaper to it, and a pitman con-
necting said block with the crank of the
crank shaft, runners carried by the frame
and movable to and from the sandpapering
side of the machine, and springs holding

10
said runners normally lower than the sand-
papering surfaces of the machine.

In testimony whereof I affix my signature,
in presence of two witnesses.

CHARLES F. HAUG.
